FLEXIBLE ROTARY-HAMMER UNIT

William E. Sheeley, Toulon, Ill.

Application January 19, 1950, Serial No. 139,447

8 Claims (Cl. 241—194)

1

This invention relates to hammer units for use in cornstalk grinding, shredding and pulverizing machinery and in feed and grain grinding machinery using the hammer mill operation.

The primary object of the invention is to provide a hammer unit of the character indicated above comprising a resilient connecting medium secured at one of its ends to a rotary shaft and at its other end to a hammer head.

Another object of the invention is to provide a hammer unit of the character indicated above the resilient medium of which comprises a link chain or the like, one end portion of which is pivotally secured to the shaft and to the other end portion of which the hammer head is pivotally attached.

A further object of this invention is to provide a hammer unit of the character indicated above the link chain of which is prevented from collapsing by means of a helical spring surrounding the chain and resting with one of its end portions in a socket slidably attached to the shaft and engaging with its other end portion another socket formed in the inner portion of the hammer head.

The invention consists in the details of construction and in the combination and arrangement of the several parts of my improved flexible rotary hammer unit whereby certain advantages are attained, as will be hereinafter more fully set forth.

In order that my invention may be better understood, I will now proceed to describe the same with reference to the accompanying drawings, wherein:

Figure 1 is an end view partly in elevation and partly in section of a hammer unit secured to a rotary shaft;

Figure 2 is a view in section taken substantially on the line 2—2 of Figure 1;

Figure 3 is a view in section taken substantially on the line 3—3 of Figure 1;

Figure 4 is a view in elevation of a hammer head of a slightly modified form and adapted to be used in connection with a hammer unit in accordance with the present invention;

Figure 5 is a diagrammatical view showing a resilient hammer unit arranged in working position inside a supporting drum of a cornstalk shredding, grinding and pulverizing machine;

Figure 6 is a side view partly in elevation and partly in section of a slightly modified resilient hammer unit; and

Figure 7 is a view similar to Figure 6 illustrating another slightly modified form of a resilient hammer unit.

2

The hammer unit as herein embodied comprises a hammer head 10 preferably made from cast steel, tool steel or other suitable material and having a cubic form. It is, however, to be understood that the hammer head 10 may have any suitable shape or form. In one side, hereinafter called the inner side, of the hammer head 10 a shallow square hollow 11 is provided and is disposed centrally of said inner side. Centrally of the bottom of the square hollow a narrow slot-like hollow 12 is provided extending partway into the hammer head 10, and an axial central member consisting preferably of a link chain C. One end link 13 of the link chain C fits loosely into the slot-like hollow 12 in the hammer head 10 and is pivotally fastened in said head by means of a rivet 14 or the like extending through the hammer head 10 and the end link 13.

On a rotary drive shaft 15, a drum 16 may be formed or secured in any suitable manner and a pair of mounting rings 17, preferably made from steel, are mounted on the drum 16 and are secured thereto by welding or the like as best indicated at 18 in Figure 2. The two rings 17 are spaced from each other so that the other end link 19 can be loosely inserted between the mounting rings 17. A bolt 20 or the like extends through the two rings 17 and the second end link 19.

A socket 21 has at one of its ends a rectangular base 22 which is curved lengthwise concavely in downward direction. Centrally of the base 22 a longitudinal hollow 23 is provided extending over the entire length of the base. The bottom of the hollow 23 is curved concavely and the curvatures of the base 22 and the bottom of the hollow 23 is such that they are concentrical with each other and that the bottom of the hollow 23 fits slidably on the peripheral surfaces of the mounting rings 17. The width of the longitudinal hollow 23 is such that the two mounting rings 17 fit snugly into said hollow.

Centrally of the bottom of the hollow 23, a rectangular hole 24 is provided, the longitudinal lips of which are rounded as shown best at 25 in Figure 4. The length and width of the rectangular hole 24 are such that the second end link 19 of the link chain C can extend snugly through said hole.

A helical spring 26 surrounds the chain link C and one end portion of said spring is disposed in the hollow 11 in the inner side of the hammer head 10 and the other end portion of the spring 26 is located in the socket 21. The respective lengths of the link chain C and the helical spring

26 are such that the pressure of the spring 26 prevents accidental collapse or kinking of the chain C but forms with the chain C a flexible connecting medium for attaching the hammer head to the mounting rings 17 or to the rotary drive shaft 15.

The sliding fit of the socket base 22 on the mounting rings 17 allows a limited rotary movement of the hammer unit with respect to the rings.

If desired a plurality of hammer units of the kind described above can be secured in the described manner to the mounting rings 17 and the several hammer units are then disposed equidistantly from each other.

In Figure 4 a slightly modified form of a hammer head is shown. This hammer head 27 is made preferably from cast steel or tool steel and is shaped similar to the hammer head 10 described above with the exception that the surface opposite to the inner surface of the hammer head is serrated as indicated at 28 in Figure 4.

As shown in Figure 5 the resilient rotary hammer unit constructed in accordance with the present invention may be installed concentrically with a semi-cylindrical thrasher drum 29 supported in the usual manner on wheels on a sub-frame (not shown).

The rotary hammer unit rotates in the embodiment shown in Figure 5 in clockwise direction and a supply of cornstalks 30 is provided under the thrashing drum 29.

A plurality of breaking bars 31 are secured longitudinally on the inside surface of the drum wall and are disposed equidistantly from each other. The breaking bars 31 extend radially inward from the drum wall so far that the hammer head 10 just clears said bars, which preferably have a triangular cross section.

The hammer head 10 engages some of the cornstalks 30 and carries them upwardly toward the breaking bars 31. The stalks are wedged between the bars 31 and the hammer head 10 so tightly that this obstruction holds the hammer head 10 back by overcoming the pressure of the helical spring 26 as shown in broken lines at 32 in Figure 5. When the hammer head 10 is held back far enough it will clear the obstacle and the pressure of the spring 26 combined with the rotary movement of the shaft 15 swings the hammer head 10 forwardly into the position indicated in broken lines at 33 in Figure 5 so that it delivers an exceptionally strong blow onto the partly treated cornstalk located between the breaker bars 31, crushing them entirely.

When a plurality of resilient hammer units are arranged on the shaft 15 the cornstalks 30 are subjected continuously to the above described treatment and are crushed and pulverized thoroughly.

In Figure 6 a slightly modified hammer unit is illustrated comprising the parts forming the above described hammer head parts with the exception of the link chain C, which is replaced by a flat steel bar 34 secured at one of its ends pivotally to the hammer head 10 by the bolt 14 or the like, and the other end portion of which extends through the socket 21 and its base 22 and is pivotally connected to the mounting rings 17 by a bolt 20 or the like.

In Figure 7 another modified hammer unit is illustrated and in this embodiment the flat steel bar 34 is replaced by a round rod 35 having its outer end portion shaped into an eye 36 and its

inner end portion into an eye 37. The outer eye 36 extends into the hammer head 10 and is secured thereto by the bolt 14 and the inner eye 37 is located between the mounting rings 17 and is attached to them by the bolt 20.

From the foregoing description it is thought to be obvious that a flexible rotary hammer unit constructed in accordance with my invention is particularly well adapted for use by reason of the convenience and facility with which it may be assembled and operated.

I claim:

1. A hammer unit of the class described including a hammer head, a pair of mounting rings mounted on and secured to a rotary shaft, a link chain, one end link of said chain being secured to the hammer head and the other link being attached to the mounting rings, and a helical spring surrounding the chain and preventing it from collapsing.
2. A hammer unit of the class described including a hammer head, a pair of mounting rings mounted on and secured to a rotary shaft, a link chain, one end link of said chain being secured to the hammer head and the other end link being attached to the mounting rings, a helical spring surrounding the chain and preventing it from collapsing, a socket, and a base on said socket and fitting slidably on the peripheral surfaces of the mounting rings, the chain extending through an opening provided in the socket base, one end portion of the spring being disposed in the socket and the other end portion of the spring being located in a hollow provided in the inner side of the hammer head.
3. A hammer unit of the class described including a hammer head, a pair of mounting rings mounted on and secured to a rotary shaft, a bar secured at one of its ends to the hammer head and with its other end portion disposed between and secured to the mounting rings, and a helical spring surrounding said bar and tending to hold the bar in radial position to the rings.
4. A hammer unit of the class described including a hammer head, a pair of mounting rings mounted on and secured to a rotary shaft, a rod secured with one of its end portions to the mounting rings, the hammer head being attached to the other end portion, and a helical spring surrounding the rod and tending to hold it in radial position to the rings.
5. A hammer unit of the class described including a hammer head, an elongate element coupling the head to a rotary shaft for swinging movement relative to the shaft, and a resilient member for connection between the head and the shaft for constantly urging the elongate element to maintain a radial position relative to the shaft, said resilient member comprising a coil spring encircling said elongate element and compressed between the head and the shaft.
6. A hammer unit of the class described for mounting on a rotary shaft, comprising a body adapted to encircle the shaft, the body having a periphery directed away from the shaft, a hammer head, an elongate member pivotally connected at one end with said body to extend radially outwardly from the shaft, means coupling the hammer head with the other end of the elongate member, a support element carried on the periphery of said body, and a spring interposed between said support element and the head and exerting a radial thrust force outwardly against the head.

7. The invention as defined in claim 6, wherein said elongate member comprises a chain.

8. The invention as defined in claim 6, wherein said elongate member is of substantially rigid form.

WILLIAM F. SHEELEY.
